WALL CONSTRUCTION

Norman A. Brand, Lancaster, Pa., assignor to
Armstrong Cork Company, Lancaster, Pa., a
corporation of Pennsylvania

Application August 1, 1931, Serial No. 554,501

10 Claims. (Cl. 20—4)

This invention relates to a wall construction and is particularly directed to an improved wall covering and binding strip employed therewith. It has been proposed to substitute a flexible hard surface covering of the linoleum-felt base type for ceramic tiles in the wall construction of bathrooms, kitchens, and other rooms where a sanitary, impervious, washable wall surface is desired. Great difficulty, however, has been encountered in placing the surface covering in such fashion that a neat and strong edge is assured. Appearance is a great consideration in an installation of this character, but it is also highly important that the edge of the surface covering be protected and supported in a suitable fashion. There is always danger of soap and water getting back of the covering and loosening it, or of the edge being caught and torn loose unless adequately protected. Various schemes have been suggested but they have been open to numerous objections. A suitable binder must be of relatively low cost, readily fitted on the job without undue labor and expense, and of such character that when put in place it is in harmony with the surface covering and does not unduly reverse its manner of attachment.

I provide a binder strip comprising a core having a wrap of a hard surface covering material thereover, such wrap being preferably of the same character as the material employed for covering the room surface proper. The core is preferably made of wood or some other nail receiving material so that nails may be driven through it into the wall to hold it in place. The covering may have a pattern of such character as to provide depressions which will accommodate the nail heads. For instance, the covering may be in simulation of tile, in which case interliners will be provided of sufficient size to take the head of a finishing nail. When the strip is put up, the nails will be driven at the interliners and the heads sunk with the nails set. The heads may then be puttied over and the putty, lying in the depressions of the pattern, will not be apparent except on the closest inspection.

I provide on the back of the binder strip an offset to receive the edge of the surface covering material. This offset may be readily formed bylapping the wrap of covering material on the back of the core. This gives an offset which is exactly the right thickness to accommodate the wall covering.

In order to simplify the installation, I provide corner units, which corner units preferably have insufficient flexibility that they may be fitted into a corner of a room despite irregularities therein such as are normally found in house construction.

In the accompanying drawing illustrating a present preferred embodiment of the invention,

Figure 1 is a perspective view of a wall, and Figure 2 is a horizontal section of a corner unit. Figure 1 shows a wall W having a nail receiving strip 2 incorporated therein, although this is not essential, and, if desired, the nails may be driven into the wooden studding. The lower portion of the wall is covered with a flexible hard surface covering of the linoleum-felt base type, as indicated at 3. This covering is made in a tile pattern formed of tile portions 4 and interliners 5. It is desired that the tile effect be carried part of the distance up the wall, and that a plain surface material 6, or a material of another pattern, be placed thereabove. In certain cases, of course, it will be desirable to carry a single pattern up to the ceiling and to bind the material adjacent the ceiling. In either case I employ a binder strip as indicated generally by the reference character 7. This binder strip comprises a wooden core 8 having a wrap 9 of the surface covering material therearound. The material is lapped over on the back as indicated at 10. This gives an offset whose depth is equal to the thickness of the covering material and therefore just sufficient to receive the wall covering 3 and still give uniform bearing across the entire back of the binder strip. The exposed edge 11 of the material covering the binder strip serves to align the strip properly with the wall covering material, or if the edge of the covering material 3 has not been accurately cut the strip may be adjusted up or down sufficiently, while continuing to serve its function of overlying the edge portion of the covering 3, so as to properly position the binder.

It will be noted from Figure 1 that the covering material on the binder strip is in simulation of tile, having interliners 5a. These are of sufficient width to accommodate the heads of finishing nails which are driven in and counter-sunk as indicated at 12, the hole above the nail head being filled with putty as indicated at 13. The putty will be smoothed down to be flush with the bottom of the groove 5a representing the interliner, and is preferably of the same color as the color of the interliner. This makes the method of fastening imperceptible except upon the closest scrutiny.

The wrap of covering material on the core 8 is preferably secured thereto by a cement, but, as will be noted from an examination of Figure 1, the pressure of the core against the wall securely holds the covering in place once the strip has been attached.

Figure 2 shows a corner strip. It comprises a core 8a having portions extending at an angle to one another, the unit being covered with a wrap 9a of material formed in the same fashion as the binder strip shown in Figure 1. Two portions of the corner strip in Figure 2 are joined at an angle

slightly greater than a right angle as shown by the dotted lines of Figure 2, which lines are at right angles to one another. The core 8a may be cut from a piece of wood, or the wood may be bent, or a composition may be employed, but in any event it should be sufficiently springy to permit of the corner piece accommodating itself to the walls of the room when the holding nails are driven home. The angularity between the two portions is sufficiently great to take care of irregularities of construction. If the corner angle is slightly greater than 90°, the piece will nevertheless fit and bear closely against the wall at all points without any tendency for the ends 14 to spring outwardly. If the room corner is 90° or less, the two portions of the corner piece will be sprung to fit when the nails are driven home.

Figure 2 shows a unit, each of whose portions has a length approximating a tile unit. This provides an interliner space at 15 at the junction of the two portions and interliner spaces 16 at the ends of the unit. A nail may be driven in at 15 into the corner, and nails may be driven at a slight angle at 16. Straight pieces of binder strip are then butted against the ends 14 and secured in place, the joint being substantially concealed by the fact of it occurring at an interliner. Figure 2 shows an inside corner, but an outside corner may likewise be formed. For an outside corner the angle between the two portions is preferably slightly less than 90°.

When the binder strip is in place, full and adequate protection is afforded for the edge of the surface covering 3 and a neat and ornamental structure is presented. If near the ceiling it is similar to a molding and presents as good an appearance as when placed part-way up the wall. Figure 1 shows a surface covering 6 above the binding strip and, if desired, the slight recess at 17 may be sealed off with varnish, putty, or some other suitable material.

While I have illustrated and described a present preferred embodiment of the invention, it will be understood that it is not thus limited but may be otherwise embodied or practiced within the scope of the following claims.

I claim:

1. A binder strip comprising a core having a wrap thereover of a flexible hard surface covering of the linoleum felt base type, the strip having a face adapted to be placed against a wall, the wrap of covering material extending over a portion at least of said face, then around the core and then onto said face in overlapping relation with itself so as to provide an offset.

2. A binder strip comprising a core having a wrap of a flexible hard surface covering material thereover, the wrap of covering material extending over a portion at least of the rear face of the core, then around the core and onto the rear face and terminating in an offset, the covering having a pattern of such character as to provide depressions of sufficient size to accommodate fastening means.

3. A binder strip comprising a core having a wrap of a flexible hard surface covering material thereover, the wrap being lapped over on itself on a face of the core so as to provide an offset.

4. A binder strip comprising a nail-receiving core having a wrap of a flexible hard surface covering material thereover, the strip having a face adapted to be placed against a wall, the wrap of covering material extending over said face, then around the core, and then onto said face again, the wrap terminating in an edge lying along said

face, the portion adjacent the edge overlapping the first-mentioned portion of the covering material whereby there is provided on said face an offset equivalent to the thickness of the covering material.

5. In combination with a room surface, a flexible hard surface covering material extending over a portion thereof and terminating in an edge, and a binder strip secured to the room surface and concealing such edge, the binder strip comprising a core having a wrap of said covering material thereover, the wrap of covering material extending across the face of the core which is adjacent the room surface, then extending around the core, and then onto the first-mentioned face and terminating in an edge on such face, the edge portion of the covering material for the core overlapping the first-mentioned portion of covering material on such core whereby there is provided an offset, the edge of the hard surface covering on the room surface terminating in such offset.

6. In combination with room surfaces disposed at a projecting angle constituting a corner, flexible hard surface covering material thereover, the covering material terminating in an edge, and a binder strip comprising a core shaped to extend around said corner and secured against the room surfaces so as to conceal said edge, the core having a facing of a flexible hard surface covering material, the strip, after wrapping, having an offset on its rear face to receive said edge, and an abutting binder strip of like character, the binder strips having depressions thereon, there being a depression at the point of juncture.

7. In combination with a room surface, a sheet of covering material thereover terminating in an edge, and a binder strip for binding said edge comprising a core having a wrap thereover of a flexible hard surface covering of the linoleum felt base type, the wrap of covering material extending over a portion at least of the rear face of the core, then around the core and onto said face again in alignment with the sheet of covering material on the room surface.

8. In combination with a room surface, a flexible hard surface covering material extending over a portion thereof and terminating in an edge, and a binder strip for binding said edge comprising a core having a wrap thereover of a flexible hard surface covering, the strip, after wrapping, having an offset on its rear face to receive said edge.

9. In combination with a room surface, a flexible hard surface covering material extending over a portion thereof and terminating in an edge, and abutting binder strips for binding said edge, each binder strip comprising a core having a facing of a flexible hard surface covering material wrapped thereover and having an offset on its rear face to receive an edge of the covering material on the room surface, the binder strips having depressions on their surface, there being a depression at the point of juncture.

10. A binder strip comprising an angular shaped core of springy material having oppositely extending portions joined at an angle differing slightly from a right angle, shaped to extend around a corner and having a wrap of flexible hard surface covering material extending over a portion at least of the rear face of the core, then around the core and onto the rear face and terminating in an offset adapted to receive the edge of a surface covering material.
